Letters Patent No. 22,800 Dated Mar. 13th 1866
Design for a Trade mark -

The schedule referred to in these Letters Patent, making part of the same,

To all whom it may concern:

Be it known that, I, A. W. Fagin of St. Louis in the County of St. Louis and State of Missouri have originated and designed a new design for a trade mark, of which the following is a full, clear, and exact description, reference being had to the accompanying accompanying drawing part of this specification.

This trade mark as is seen in the drawing, consists of a hand holding four cards spread out in the form of a fan, which are the four aces of a pack, i.e. the ace of hearts, ace of clubs, ace of diamonds, and ace of spades. It is intended to use this device principally in the flour trade, The four aces being the best hand in the game of "poker", do by implication the barrel or other receptacle to which this trade mark is applied, will be understood to contain the best quality of flour or other material with which it is filled. This design may be enclosed within a proper frame or circle within which any suitable inscription may be made, such as "A. W. Fagin, 190 extra" or any other inscription indicating the quality and grade of the flour or other article.

What I claim as my invention and desire to secure by Letters Patent is The design for a trade mark substantially as herein described and set forth...
